UNITED STATES PATENT OFFICE.

LAWRENCE S. McCOMBS, OF HUNTINGTON, INDIANA.

DESIGN FOR A DISPLAY-RACK FOR SHOES.

56,883.

Specification for Design.

Patented Jan. 4, 1921.

Application filed July 26, 1920. Serial No. 399,196. Term of patent 7 years.

To all whom it may concern:

Be it known that I, LAWRENCE S. McCOMBS, a citizen of the United States, residing at Huntington, in the county of Huntington and State of Indiana, have invented a new, original, and ornamental Design for Display-Racks for Shoes, of which the following is a specification, reference being had to the accompanying drawing, forming part thereof.

Fig. 2 is a horizontal section taken on line 2—2 of Fig. 1;

Fig. 3 is an end elevation;

Fig. 4 is a vertical transverse section taken on line 4—4 of Fig. 1.

I claim:

The ornamental design for a display rack for shoes, as shown.

LAWRENCE S. McCOMBS.
